United States Patent Office

Des. 203,590
Patented Feb. 1, 1966

203,590

BUILDING BLOCK

Howard M. Davis, 229 W. Washington Ave.,
Alpena, Mich.

Filed Sept. 28, 1964, Ser. No. 81,905

Term of patent 14 years

(Cl. D18—2)

Fig. 2

Fig. 3

Fig. 1

FIG. 1 is a bottom plan view of a building block showing my new design;

FIG. 2 is a front elevational view thereof;

FIG. 3 is an end view thereof; and

FIG. 4 is a front perspective view thereof.

I claim:

The ornamental design for a building block, substantially as shown.
